UNITED STATES PATENT OFFICE.

OLIVER B. DOBBINS, OF CHAMPAIGN, ILLINOIS.

CLOSURE OPERATOR.

Application filed March 17, 1926. Serial No. 95,294.

The present invention relates to improvements in closure operators and has reference more particularly to a highly novel yet simple means for effecting the actuation of the 5 swinging doors of a garage, shed, or barn by the wheels of a vehicle passing over a trip mechanism located at a point remote of the doors.

A further object is to provide a closure 10 operator which will at all times be positive and efficient in its operation, the same being further of such construction as to enable the same to be installed without interfering with the access through the opening for which 15 the doors are provided and without further necessitating any material alterations of the garage or the doors.

A still further object is to provide a closure 20 operator which is simple in construction, inexpensive, strong and durable, and further well adapted to the purpose for which it is designed.

Other objects and advantages of the invention will become apparent during the 25 course of the following description taken in connection with the accompanying drawings.

In the accompanying drawings forming a 30 part of this application, and in which like numerals designate like parts throughout the same:

Figure 1 is a top plan view of the closure 35 operator embodying my invention, showing the same associated with the swinging doors of a garage, and illustrating the arrangement of the parts when in their normal positions, and when the swinging doors of the garage are closed.

Figure 2 is a similar view showing the 40 doors swung to an open position.

Figure 3 is an enlarged side elevation of the pawl and ratchet mechanism, and also the telescoping tubular members showing the manner in which the same are associated 45 with the shaft and doors of the garage respectively.

Figure 4 is an enlarged detail of the telescopic members and the coil spring surrounding the same, and

Figure 5 is a detail of the trip mechanism.

In the drawings wherein for the purpose of illustration is shown the preferred embodiment of my invention, the numerals 1 and 2 designate a pair of coacting swinging 55 doors, which provide a closure for the entrance to a garage or the like designated

generally by the numeral 3. Extending transversely and journaled at its respective ends in suitable bearings of the bracket 4 is the shaft 5. This shaft is preferably located at a point adjacent the top of the door and the supporting bracket for the shaft are supported from the rafters of the garage in the manner clearly shown in Figure 3. A ratchet wheel 6 is fixedly secured on the intermediate portion of the shaft, and the purpose thereof will be hereinafter more fully described.

A lever 7 is loosely mounted at its inner end on the shaft 5 adjacent the ratchet wheel 6. A pivoted pawl 8 is carried by the intermediate portion of said lever and the same cooperates with the ratchet teeth formed in the peripheral edge of the ratchet wheel 6 for actuating the shaft 5 as will be herein-after more fully described. A dog 9 is associated with the shaft supporting bracket 4 which is located adjacent the bracket wheel 5 and this dog cooperates with the ratchet teeth of the ratchet wheel 6 in preventing the rotation of the shaft in the reverse direction. The actuating dog associated with the lever 7 and the locking dog 9 are clearly illustrated in Figure 3 of the drawing.

A retractile coil spring 10 is associated with the outer free end of the lever 7 for maintaining the latter in its normal position.

A crank arm 11 is fixedly secured to the outer ends of the shaft 5.

A pair of telescopic tubular members 12 and 13 respectively are associated with each of the doors, and as is more clearly illustrated in Figure 4 of the drawings, the inner end of the tubular member 13 is slidably disposed within the outer end of the larger tubular member 12. The inner opposed ends of the telescopic tubular members 12 and 13 are open, while the outer ends thereof are closed. The closed outer end of each of the tubular members 12 is connected to the outer end of the respective crank arms 11 which are secured on the outer ends of the shaft 5 through the medium of a ball and socket connection designated generally by the numeral 14. A similar connection 15 affords a means whereby the outer ends of the smaller tubular member 13 may be hingedly secured to the inner sides of the doors 2 and 3 respectively. A plate 16 which carries one of the portions of the joint whereby the outer ends of the telescopic members 13 may be connected to the doors is secured to the

inner side of each of the doors at a point adjacent the upper edge thereof and also adjacent the hinged side thereof. This construction is clearly shown in Figures 3 and 5 of the drawings.

A retractile coil spring 17 encircles the inner open end of the tubular member 12, one end of this coil spring extending into the slot 18 which extends longitudinally in the intermediate portion of the tubular member 12, the other end of the coil spring extending into the slot 19 which extends longitudinally in the other tubular member 13. The respective ends of the retractile coil spring 17 are normally disposed adjacent the inner opposed ends of the longitudinally extending slots 18 and 19 respectively, as is clearly shown in Figure 4, and also the inner opposed ends of tubular members 12 and 13 so that either pushing the telescopic members together or pulling them apart will expand the spring.

An actuating cable 20 is connected to the outer end of the rockable lever 7, and extends forwardly of the garage, and is trained around a suitable guide pulley 21 which is preferably arranged adjacent the center of the door opening at the top thereof in the manner clearly shown in Figures 1 and 3 of the drawings. The cable then extends laterally to one side of the garage where it is trained over another pulley 22 and the outer end of the cable extends forwardly of the entrance to the garage and is connected to a suitable trip mechanism shown in Figures 1 and 5.

This trip mechanism includes a pair of relatively short posts or blocks indicated by the numerals 23 and 24 respectively. These blocks are set in the entrance to the garage, in the roadway, a suitable distance from the doors of the garage. The block 24 is preferably set in the road bed adjacent the side edge thereof, while the complementary block or post 25 is arranged in the intermediate portion of the road bed and preferably at such a distance with respect to the block 24 so as to enable at least one pair of aligned front and rear wheels 50 of the vehicle to pass between the spaced blocks or posts.

A chain 26 is secured at one end to the block 25, the other end of the chain being trained over a pulley 27 mounted on the top of the block 24, and then extending downwardly along the side of the block 24 and is connected to the outer end of the cable 20. An additional pulley 28 is supported on the outer side of the block 24 adjacent the bottom thereof and the outer end portion of the cable 20 is trained thereover. The chain 26 is normally maintained taut and the blocks 24 and 25 which are arranged in the roadway remote of the garage doors are of such height as not to interfere with the

passing of the vehicle thereover. The chain 26 is normally maintained taut through the medium of the coil spring 10 which returns the lever 7 to its normal position.

The operation of the closure operator embodying the present invention may be briefly stated as follows: Normally the parts are arranged as shown in Figure 1 of the drawings. When a vehicle approaches the garage, as soon as the outer front wheel of the vehicle passes over the chain 26, the trip will be depressed and will simultaneously cause an outward pull to be exerted on the cable 20 which will result in the forward or outward swinging movement of the lever 7 against the tension of the coil spring 10. The pawl 8 which is carried by the lever 7 will turn the ratchet wheel and the shaft 5 on which the ratchet wheel 6 is fixed a quarter of a revolution. Simultaneous with the turning of the shaft 5 a quarter of a revolution, the crank arm 11 will also swing upwardly and forwardly a quarter of a revolution. This movement of the crank arms will tend to exert an outward thrust on the doors 1 and 2 through the medium of telescopic tubular members 12 and 13.

When the rear outer wheel of the vehicle passes over the chain 26, the shaft will be caused to rotate another quarter of a revolution, as will also the crank arms 11. During the outward swinging movement of the doors 1 and 2, the telescopic members 12 and 13 will become shorter in length, at the same time, retractile coil springs 17 will expand due to the respective ends of the tubular members being in engagement with the respective ends of the coil spring. When the doors 1 and 2 are in the open position as shown in Figures 2, 3, and 4 of the drawings, the vehicle will be permitted to enter the garage without necessitating the operator having to leave his seat and open the doors, thus saving considerable time and labor.

On the vehicle leaving the garage, the two wheels on one side of the vehicle will automatically close the doors by a reversal of the above operations causing the shaft 5 to make a half revolution compelling the crank arms 11 to swing inward, the telescopic members 11 and 13 will be expanded from their normal position, the looped ends of spring 17 will be caught by the slots in the telescopic members and caused to expand and in returning to normal, will pull the swinging doors shut.

The doors may be returned to a closed or open position, by hand by pulling on the cable 20 so as to cause the shaft 5 to complete another half a revolution and during the completion of the last half of the revolution, the crank arms 11 and in such a position as to cause the doors 1 and 2 to swing

inwardly to a closed position or outwardly to an open position as desired.

While I have shown the preferred embodiment of the invention it is to be understood that minor changes in the size, shape, and arrangement of parts may be resorted to without departing from the spirit of the invention and the scope of the appended claims.

10 Having thus described the invention, what I claim as new and desire to secure by Letters Patent is:—

1. Means for actuating a swinging closure for a garage comprising a shaft supported transversely in the garage, a pawl and ratchet mechanism associated with the shaft, means operable by a vehicle either leaving or approaching the garage for actuating the pawl and ratchet mechanism, and thereby 20 operating the shaft, an operative connection between the shaft and said closure whereby the latter will be simultaneously operated with the shaft, said connection comprising a crank arm having one end thereof fixed to 25 the shaft, a pair of telescopic tubular members secured at their outer ends to the swinging closure and the outer end of the crank arm respectively, each of said telescopic members being slotted longitudinally, and a 30 retractile coil spring encircling the inner opposed ends of the telescopic members, the ends of the coil spring being disposed within the slots of the respective telescopic members and normally disposed adjacent the inner 35 ends of the slots and so arranged as to return the two telescopic members to their normal position when the two telescopic members are either pulled apart or shoved together.

40 2. Means for actuating the swinging closure for a garage comprising a shaft supported transversely in the garage, a ratchet wheel secured on the shaft, a crank arm fixed at one end on said shaft, a combination

45 collapsing and expanding opening connection between the other end of the crank arm and said closure, a lever rockably mounted

on the shaft, a pawl carried thereby and adapted for engagement with the ratchet wheel for effecting the rotation of the shaft, 50 and a simultaneous movement of the closure, a trip mechanism arranged at a point remote of the closure, a cable connecting said trip mechanism with said lever whereby the lever is operated when the trip mechanism 55 is actuated, and a coil spring associated with said lever for securing the same to its normal position and simultaneously returning the trip mechanism to its normal position.

3. Means for actuating the swinging closure for a garage comprising a shaft supported transversely in the garage, a ratchet wheel secured on the shaft, a crank arm fixed at one end on said shaft, a connection between the other end of the crank arm and 60 said closure, a lever rockably mounted on the shaft, a pawl carried thereby and adapted for engagement with the ratchet wheel for effecting the rotation of the shaft, and a simultaneous movement of the closure, a 65 trip mechanism arranged at a point remote of the closure, a cable connecting said trip mechanism with said lever whereby the lever is operated when the trip mechanism is actuated, a coil spring associated with said 70 lever for securing the same to its normal position and simultaneously returning the trip mechanism to its normal position, said trip mechanism including a pair of posts arranged in the roadway, one of said posts 75 being disposed adjacent the outer side of the roadway, the other post being disposed in the intermediate portion thereof so that one pair of aligned wheels of a vehicle may pass between the posts and a flexible member 80 secured at one end to said posts, said flexible member extending over the other post and being secured to the cable, one pair 85 of aligned wheels of the vehicle being adapted to pass over the flexible member and depress the same.

In testimony whereof I affix my signature.

OLIVER B. DOBBINS.
